WALTER BIXBY, OF BOSTON, AND CHARLES LEA, OF MILTON, MASSACHUSETTS, ASSIGNORS TO SHAWMUT ENGINEERING COMPANY, OF BOSTON, MASSACHUSETTS, A CORPORATION OF MASSACHUSETTS.

TUFT-YARN CARRIER FOR LOOMS.

Application filed February 27, 1926. Serial No. 91,231.

This invention relates to pile fabric weaving in which the pile is formed by the insertion of rows of yarn tufts in the fabric during the weaving operation, and it has particular reference to that class of tuft-weaving looms in which the tuft yarn frames, instead of being transferred from their carrier-chain to deliver yarn directly to the fabric, remain in the chain or supporting carrier while yarn-transferring and inserting devices, in the form of nippers or otherwise, are employed to remove tufts of yarn from the tuft-yarn frames for insertion into the fabric being woven.

It is the object of the present invention to provide an improved tuft-yarn carrier of this type which shall be simple in its construction, cheap to manufacture and at the same time making provision for convenient replacement of such parts as may become accidentally injured or deformed while in service. In general the improvement comprises a suitable carrier frame provided with a longitudinal yarn-positioning and spacing member, in combination with a series of transverse guides which are reliably mounted beneath the yarn-positioning member to separate the individual yarn tufts and also provide removable guides for the nippers or yarn-transferring devices. These and other features of the invention will be explained in the following specification and will be defined in the claims hereto annexed.

In the accompanying drawings several forms of embodying the principles of this invention are illustrated, in which:

Figure 1 is a front elevation of a carrier-frame containing this improvement.

Figure 2 is a cross sectional view thereof.

Figure 3 is a detail perspective view showing the underside of a portion of the yarn-positioning and spacing means.

Figure 4 is a detail showing, in perspective, one of the removable yarn-separating guides.

Figure 5 is a perspective view from above of a portion of the yarn-positioning member showing one means of retaining the guide-locking rod in position.

Figure 6 is a front elevation showing a modification of the improvement.

Figures 7 and 8 are enlarged details showing, respectively, a front elevation and a

cross section of the form illustrated in Figure 6.

Figures 9 and 10 are similar detail views of another modification.

For purposes of illustration we have shown the improvement applied to a tuft yarn frame of well known construction which embraces a tubular carrier-bar 1, suspension brackets 2, having suspension hook-latches 3 and having journal bearing members 4 for the support of rotatable spools 7, and also having intermediate spool-bearing brackets 5 equipped with self-locking latches 6 of a well-known type which form no part of the present invention.

The yarn-positioning and spacing member, in this form, comprises a longitudinal plate or strip 10, preferably of pressed metal, provided with a depending front flange 10^a having guide-receiving apertures or slots 10^b regularly spaced apart and registering with apertures 10^c, in the rear depending flange 10^e.

A series of transverse guides comprising, in this case, a thin plate 12, formed at one end with a tenon 12^a, and at the other end with an open notch or recess 12^b, are so dimensioned as to be insertable through the slots in the rear flange 10^e, and have their tenons project through the forward row of slots 10^b. The notches 12^b are made of sufficient depth so that they extend some distance inside of the rear flange 10^e in order to permit the insertion of a longitudinal locking rod 13, through the slots and inside of the rear flange 10^e.

The horizontal or body portion of the yarn-positioning member 10 is formed with spaced apertures 11, of sufficient size to allow each tuft-yarn element to pass through when engaged with a suitable threading needle, such as illustrated at y in Figure 10.

Preferably along the top of the yarn-spacing and positioning member 10 is disposed a longitudinal rod or wire 14 which overlaps or is immediately adjacent to the front of the yarn aperture in order to form a deflecting means for preventing the hook of the threading needle y of the threading machines, which are used to draw the tuft-yarns through the positioning member, from catching against the edge of the yarn aperture. These yarn-positioning members should be

secured to the carrier-frame with great precision. Furthermore, as it will be of advantage to be able to change the pitch or spacing of the guides as a greater or less number of tuft-yarns to the inch are to be employed, we have made provision for interchangeably securing different yarn-positioning and guiding means to the same carrier-frame.

10 In the present case this is accomplished by providing, at suitable intervals along the rear of the member 10, a series of apertures whose edges are upset, as shown at 15, which exactly register with openings or recesses in the bottom of the longitudinal carrier-bar. Vertical attaching bolts 16 are inserted from the bottom through these upset apertures and are engaged, at their upper ends, by locking nuts 16^a, by which the plates 10 are 20 rigidly and accurately secured in proper position on the carrier-frame, while making it possible to quickly substitute yarn-positioning members of different pitch, thereby effecting a very great saving in equipment by 25 avoiding the necessity of supplying a complete tuft-yarn frame to accommodate different kinds of work.

It will be understood that the particular form of the yarn-positioning and nipper-guiding members may be subject to considerable variation while still retaining the principle above explained. In Figures 6, 7 and 8 we have illustrated a modified form in which the yarn-positioning and spacing member 20 still consists of a longitudinal sheet or plate secured to the underside of the carrier-bar 1, by the above-described means or any other suitable means, and is provided with a longitudinal front flange 22 and a longitudinal rear flange 23. The former has its extreme edge portion bent in and turned up to form a spacing lip 22^a, notched or slotted at intervals to receive one end of the transverse guide member 25 which can not move forward because the outer portion of the flange 22 is not apertured, the guide 25 being inserted through slots formed in the rear flange 23, just as in Figure 1. A similar upstanding lip 23^a, in the rear flange, is provided with slots registering with slots in the forward lip 22^a to position the rear end of the inserted guide member 25, and the accidental withdrawal of the guide is prevented by a longitudinal locking bar 24 inserted in the rear flange, as shown in Figure 8 which, while in place, prevents rearward movement through the vertical slots in the flange 23.

60 A needle protecting rod or wire 21, similar to the one previously described, extends along the front edges of the apertures 20^a through which the yarn-tufts α from the spool pass.

65 Figures 9 and 10 show a further modification in which the yarn-positioning plate

or strip 30 has a downwardly extending forward flange 32 and a rearward flange 33, whose extreme edge portions are bent outwardly instead of turned inwardly to form longitudinal lips 32^a and 33^a. As before, the guides 25 are inserted through slots in the rear flange 33 and its lip 33^a, but the locking-bar 34 is inserted in the rear flange on the outside instead of in the inside, as in the other forms described. The 70 front lip 32^a prevents forward movement of the guides 25, while the locking-bar 34, retained in place by the lip 33^a, serves as a positive stop against rearward movement of the guides until the bar is withdrawn to 80 permit replacement of any of the guides that may be injured.

Instead of providing a separate needle-deflecting member, as in the forms previously described, the forward edge portion of 85 the yarn-positioning member 30 may be struck up to form a longitudinal lip immediately in front of the yarn-positioning apertures to prevent the barb or hook of the needle from catching on its retracting move- 90 ment.

To prevent any accidental displacement of the locking or retaining member 13, means may be provided at the end of the 95 positioning member to prevent longitudinal movement thereof after it is inserted. Any suitable means may be employed for this purpose, but in Figure 5 we have shown the rear flange 10^c provided with a short extension 16 which is turned inwardly so as to overlap a portion of the end of the rod 13, just far enough to prevent endwise movement thereof, while allowing the lip 16 to be sprung outwardly to allow the bar 100 to be withdrawn.

The side flanges, in conjunction with the transverse guides, form enclosing pockets around the individual yarn tufts while affording access to the yarn on the part of the outwardly moving nippers in order to 110 grip the depending ends of the yarn tufts to transfer them, when severed, to the fabric.

To provide means for preventing the accidental retraction or slipping back of the 115 end of the yarn tufts through the positioning holes 11, we prefer, instead of making a clean cut hole, to upset the metal so as to form a slightly converging lip or burr, as shown at 10^e, leaving the rough or unpolished lower edge to frictionally engage the yarn tuft and thus retain it against 120 backward slip.

What we claim is:

1. In a yarn carrier for tuft weaving, the 125 combination with a spool-supporting frame, means for positioning the yarn tufts in spaced relation along the front of the frame, a plurality of yarn-separating guides detachably mounted beneath said positioning 130

means to separate the individual yarn tufts and guide the yarn-transferring means, and means for relatively retaining said guides against accidental displacement.

5 2. In a yarn carrier for tuft weaving, the combination with a spool-supporting frame embracing a longitudinal carrier-bar and its suspension members, of a longitudinal yarn-positioning plate having spaced perforations 10 for the passage of the individual yarn tufts secured to said carrier-bar, said plate being provided with guide-receiving apertures and a series of transverse guides removably mounted in said apertures, and means for 15 positively retaining the guides therein while permitting them to be withdrawn at will.

3. In a yarn carrier for tuft weaving, the combination with a longitudinal carrier-bar, of a yarn-positioning plate provided 20 with front and rear longitudinal flanges provided with registering apertures, a series of transverse guides inserted in each pair of registering apertures and a removable bar arranged to lock said guides against removal.

25 4. A yarn-positioning and separating member for a tuft yarn frame, embracing a longitudinal strip formed with depending front and rear flanges and having a series of spaced yarn-receiving and positioning apertures and a series of transverse yarn-separating guides arranged to form guides for yarn-transferring means when gripping the yarn.

5. A yarn-positioning and separating member for a tuft yarn frame, embracing an inverted trough-like member and a series of separate removable transverse division plates inserted in registering slots formed in the opposite sides of the trough and removable 40 means for releasably retaining said plates against withdrawal, the upturned bottom of the trough being formed with spaced apertures for the passage of the yarn tufts.

45 6. A yarn-positioning and separating member for a tuft-yarn frame, embracing a perforated top member having longitudinal flanges each having guide-receiving slots in registry with slots in the other, a series of transverse guides inserted in the registering 50 slots, a portion of one flange serving as an abutment preventing escape of the guides on

one side and a removable stop serving, when in position, to prevent their escape on the other side.

7. In a tuft yarn carrier for a loom, the 55 combination with a longitudinal carrier-bar, a yarn-positioning and separating member detachably secured thereto and comprising a longitudinal plate provided with spaced perforations for passage of the individual 60 yarn tufts, and having opposite side flanges and a series of transverse guides mounted in said side flanges, substantially as described.

8. In a tuft yarn carrier for a loom, the 65 combination with a longitudinal tubular carrier-bar, of a yarn positioning member comprising a longitudinal plate arranged to overlap the bottom of said carrier-bar and provided with spaced perforations for 70 yarn, attaching bolts passed through registering apertures in the top and bottom of said carrier-bar and in the longitudinal plate, and transverse guides mounted beneath said plate in position to guide yarn- 75 transferring means.

9. A yarn-positioning and separating member for a tuft yarn carrier, embracing in its construction a longitudinal plate having spaced perforations for the passage of 80 individual yarn tufts and provided with front and rear longitudinal depending flanges, and a series of transverse guides extending across the bottom of said plate from one flange to the other to form shallow elongated pockets around the individual yarn tufts.

10. A yarn-positioning and separating member for a tuft yarn carrier, embracing in its construction a longitudinal plate having spaced perforations for the passage of individual yarn tufts, the edge of each of said perforations being formed into a projecting lip adapted to embrace the inserted 90 yarn tuft and prevent its accidental withdrawal from the positioning perforation, substantially as described.

In witness whereof, we have subscribed the above specification.
